(57) **CLAIM**

The ornamental design for a valve as shown and described.

DESCRIPTION

FIG. 1 is a front perspective view of a valve showing our new design;

FIG. 2 is a rear perspective view thereof;

FIG. 3 is a front elevational view thereof;

FIG. 4 is a right side view thereof;

FIG. 5 is a rear elevational view thereof;

FIG. 6 is a left side view thereof;

FIG. 7 is a top plan view thereof; and,

FIG. 8 is a bottom view thereof.

The broken lines in the drawings denote the boundaries of the claim and form no part thereof.

1 Claim, 4 Drawing Sheets
